FIRE CONTROL MECHANISM

Clark S. Campbell, Ilion, N. Y., assignor to Remington Arms Company, Inc., Bridgeport, Conn., a corporation of Delaware

Application April 5, 1955, Serial No. 499,397

3 Claims. (Cl. 42—69)

This invention relates to fire control mechanism adapted to be utilized with either manually operated or autoloading firearms.

The fire control mechanism shown in Patent No. 2,675,638, issued April 20, 1954, to L. R. Crittenden has wide application to a variety of firearms manufactured by the Remington Arms Company, Inc., several of those firearms being shown in the patent. The fire control mechanism of the instant invention is designed to serve as a replacement for that of the cited patent in those instances where it is desired to improve the trigger pull characteristics with particular reference to a lighter pull, freedom from creep or backlash, and faster lock time. Such an improvement is the object of this invention.

The advantages of the so-called "blocked sear" type of fire control have long been realized and are readily applied to bolt action arms where the striker has only a straight line fore and aft movement. Insofar as I am aware, a "blocked sear" or other hammer controlling element which is urged to completely disengaged position by the force of the hammer spring has not previously been applied to firing mechanism employing the very common type of swinging hammer. A more specific object of my invention is to provide a blocked sear type of fire control for a swinging hammer firing mechanism.

The exact nature of my invention as well as other objects and advantages thereof will be readily apparent from consideration of the following specification referring to the attached drawings in which:

Fig. 1 is a longitudinal vertical sectional view through a fire control mechanism embodying my invention. The mechanism is shown in cocked position.

Fig. 2 is a similar view showing the same mechanism in fired position before relaxation of the grip on the trigger.

Fig. 3 corresponds to Fig. 1 but relates to another embodiment of my invention.

Fig. 4 is a view similar to Fig. 3, showing the same mechanism in fired position after the grip on the trigger has been relaxed.

Referring to the drawings, it may be seen that I have illustrated a fire control mechanism which would be directly interchangeable with that shown in Figs. 6 and 7 of the Crittenden patent above referred to, and which with obvious modifications could be applied to any other model shown in the patent.

Referring to the drawings by characters of reference, it may be seen that I have provided a trigger plate 1 which is essentially the same as that of the Crittenden patent and mounts a hammer 2 urged to swing upward and forward by a hammer spring 3 acting on a hammer spring plunger 4, communicating hammer spring force to the hammer. As in the Crittenden patent, the plunger 4 is arranged to impinge upon an arm 5 on the disconnector 6 and raise the tail 7 thereof whenever the hammer falls. A similar action of the disconnector is provided when rearward displacement of the breech

bolt carrier, also as shown in the patent, overrides the forwardly extending arm 8 of the disconnector.

The mechanism described thus far is substantially that of the Crittenden patent and the differences which characterize my invention are to be found in the hammer controlling means to be now described.

A rotating hammer block 9 comprises a V-shaped element mounted in the trigger plate 1 for swinging movement about a fixed pivot near the apex of the V and is 10 provided with a hammer engaging arm 10 which, in the position shown in Fig. 1, engages the hammer on the surface 11 and retains it in cocked position. A locking arm 12 extends rearwardly for engagement with an abutment on the sear 13 and a spring 14 acts between trigger plate and hammer block, applying a force in addition to the component of hammer spring force, urging the hammer block to free the hammer. Obviously, when the sear 13 is disengaged from the hammer block, the latter will effect an instant and clean release of the hammer for a minimum of lock time. The mechanical advantage which can be obtained by variations in the length of the locking arm 12 permits a decrease in the force applied to the sear and/or permits the use of a heavier hammer spring and lighter hammer for further decreasing lock time.

The sear 13 is likewise mounted for rotation on a cross pin 15 in the trigger plate and is urged to swing anti-clockwise as viewed in the drawing to a position for engagement with the hammer block by means of a force 30 applied below the pivot by a spring 16. The rear end of the spring engages the connector 17 which is swingably mounted on the upper end of the trigger 18. The connector is provided with a forwardly extending arm 19 which engages a step 20 on the sear above the pivot pin 15. Thus, the spring 16 acts in the same way as the spring of the Crittenden patent, urging the sear into engagement, urging the connector into engagement therewith, and urging the trigger finger piece 21 to its normal forward position. Thus, as the trigger is pulled rearwardly, the connector will rotate the sear clockwise, disengaging it from the hammer block and releasing the hammer to fall. The end of the arm 12 will ride up the forward surface of the sear above the abutment thereon and prevent return of the sear until after the hammer 40 has been recocked.

Another arm 22 on the connector extends forwardly along the back side of the trigger plate and overlies the rearwardly extending arm 7 on the disconnector. Thus, as the hammer falls and the plunger 4 engages the arm 5, the arm 7 is lifted, carrying with it the arm 22 on the connector and disengaging the arm 19 from the sear step 20. The same disconnecting action will result from rearward displacement of the breech bolt overriding and depressing the disconnector arm 8. The arm 8 may 50 also, as described in the Crittenden patent, be utilized as an action bar lock and provided with a manual release lever extending through a slot in the trigger plate.

Regardless of the means by which the disconnector 60 is operated, it frees the sear from the control of the trigger and will only permit the trigger to regain control when the breech block is fully locked and the trigger finger relaxed to permit the trigger to return to a normal forward position.

65 After firing, the hammer block will be turned clockwise to the limit permitted by engagement of the arm 10 with the trigger plate retaining pin 23, and the arm 12 will serve as a stop limiting anti-clockwise rotation of the sear 13 under urging of the spring 16. As the hammer 70 is returned to cocked position, it will engage the arm 12 on the hammer block rotating the block anti-clockwise into position for retention by the sear, and return

movement of the hammer will be stopped by engagement of the surface 11 with the arm 10. Obviously, over-cocking is permissible and, in fact, desirable to insure that the locking surfaces are in full engagement.

An adjustable trigger stop screw 24 may be provided in the trigger plate and is engageable with the sear to eliminate excessive movement of the trigger after release of the hammer block. The extent of trigger movement prior to release of the sear is dependent on the starting position of the trigger which is controlled by the engagement of the upper end of the trigger with the trigger plate retaining pin 25. The position may be controlled by selective assembly, by fitting of the trigger at assembly, or another adjustable trigger stop screw, not shown, may be provided to control this function. The usual type of cross bolt safety 26 is also provided, and the degree of trigger movement after release of the sear may be controlled as noted above, depending upon the engagement with the sectioned body of the safety 26 or upon another stop screw, not shown, to prevent trigger stop or overtravel.

Summarizing the operation of my improved fire control, it will be seen that pulling of the trigger 21 urges the connector 17 forward and swings the sear 13 clockwise. This releases the hammer block 9 which swings clockwise to release the hammer 2. The fall of the hammer permits the plunger 4 to engage the arm 5 on the disconnector, raising the arm 7 and disengaging the connector arm 19 from the sear step 20. The sear is thus released from control of the trigger, giving the sear freedom to swing anti-clockwise into position to engage the hammer block arm 12 when the hammer is cocked again.

In the embodiment shown in Figs. 3 and 4, a similar combination of elements is provided and where parts are substantially similar they have been given similar reference numerals. In this embodiment the hammer blocking member 27 is mounted behind the hammer on the pivot 15 and engages with a surface 28 on the hammer 2. The sear 29 is mounted on a pivot 30 and, when its front end is raised, releases the hammer block by disengaging from the corner 31 thereof. When the hammer block is so released, the hammer falls and the action of the spring 32 tends to return the hammer block to its former position. If the hammer block were permitted to return in this way, it would interfere with cocking of the hammer, so I have in this embodiment provided a latch 33 which is held inoperative whenever the hammer is fully cocked. As the hammer moves from cocked position, it disengages from the latch 33 and, since the hammer block is then necessarily out of the path of the hammer, it will be caught and retained by the latch until the hammer is again returned nearly to cocked position.

In this embodiment, the sear 29 is operated by a trigger 34 mounted on the pivot pin 15 and provided with a connector 35 engaged by a spring 36 and urged thereby to a position extending across between the trigger 34 and an adjustable contact point 37 on the sear. This connector is, like those of the patent and the embodiment of my invention already described, provided with a forwardly extending arm 38 which lies along the back side of the trigger plate and overlies the rearwardly extending arm 7 on the disconnector. As in the case of the other embodiments, a cross-pin safety 26 may be provided and, in this instance, can serve to positively block movement not only of the trigger 34 but of the sear 29 as well.

To summarize the operation of this embodiment, and starting in the position shown in Fig. 3, pulling of the trigger 34 operates through the connector 35 to disengage the sear 29 from the corner 31 of the hammer block 27. Thereupon, the hammer cams the hammer block out of the way and swings forward to fire a cartridge. As the hammer moves, the latch 33 is released to catch and retain the hammer block as shown in Fig. 4,

and as the hammer completes its fall the plunger 4 engages the arm 5 and lifts the rear arm 7 of the disconnector. This lifting of the arm 7, in turn, as shown in Fig. 4, lifts the arm 38 on the connector, disengaging the connector 35 from the contact 37 on the sear and releasing the sear from control of the trigger.

As the hammer is returned to cocked position, it swings by the hammer block 27 and then releases the latch 33, permitting spring 32 to swing the hammer block into engagement with the surface 28 on the hammer. The sear 29, upon being freed from control of the trigger, swings down to engage the corner 31 and to hold the hammer block.

Assuming that trigger finger pressure has been relaxed after firing and that the breech block is closed and locked after cocking, permitting the arm 8 on the disconnector to raise, the connector 35 will swing into position to control the sear as soon as the disconnector arm 7 lowers on the completion of breech locking movement. The cross-bolt safety 26 may then be moved in the usual way to position a large diameter section in opposition both to trigger and sear to positively prevent movement of either one.

With this arrangement, quite light trigger pulls can be provided with safety, for all critical components are in reasonably good static and dynamic balance and, hence, reasonably immune to accidental shocks. The practical limit on trigger pull is that imposed by the possibility of accidental engagement of the trigger by brush, etc., or by a nervous hunter.

With this arrangement I can provide for barely perceptible trigger movement prior to actual release and for substantially no excess movement after release of the trigger. It is possible with this construction to provide a trigger pull which is close to the target shooter's ideal with the ruggedness and safety required of a practical hunting rifle.

Although I have shown only two embodiments of my invention, it will be obvious that other embodiments and modifications are possible. Accordingly, it should be noted that I consider the scope of my invention to be limited by the claims appended hereto rather than by the details of the embodiments illustrated.

I claim:

1. In a fire control mechanism comprising a pivotally mounted hammer, a thrust-piece engaged with said hammer and a hammer spring engaging the thrust-piece and urging said hammer from a cocked position to a fired position; the improvement comprising in combination a hammer blocking member pivotally engageable with said hammer to block said hammer in cocked position; a sear releasably engageable with said member to retain said member in hammer blocking position; said member being forced out of the path of said hammer to a released position by said spring-urged hammer on release of said sear; means to obstruct return of said member to blocking position until said hammer approaches fully cocked position, comprising a latch for engagement with said member in released position, said latch having a release arm disposed in the path of movement of said hammer to cocking position, whereby engagement of said arm by said hammer releases said member from said latch; a trigger; and connector means coupling said sear to said trigger for manual release, said connector means comprising a pivotal element moveable out of engagement with said sear after sear release, whereby said sear is free to return to member retaining position.

2. In a fire control mechanism comprising a pivotally mounted hammer having an angularly disposed extension thereon which is provided with a locking surface, a thrust-piece engaged with said hammer and a hammer spring engaging said thrust-piece and urging said hammer from a cocked to a fired position, the improvement comprising in combination a trigger, a sear pivotally moveable from a locking position to a released position,

a connector pivotally mounted on said trigger for moving said sear to released position, means for disengaging said connector from said sear when said sear reaches released position, hammer blocking means interposed between said sear and said hammer including a member pivotal from a first position wherein the member is retained in blocking engagement with said hammer locking surface by said sear in locking position, to a second position wherein said member frees said hammer and has a member portion retaining said sear in released position, and means for returning said member to first position comprising an element of said hammer blocking means disposed in the path of travel of said hammer for displacement by said hammer in movement to cocked position.

3. In a fire control mechanism for a firearm comprising a pivotally mounted hammer having an angularly disposed extension at its free end, a locking surface on said hammer extension, a thrust-piece engaged with said hammer and a hammer spring engaging said thrust-piece and urging said hammer from a cocked to a fired position; the improvement comprising in combination a pivotally mounted hammer blocking member having a hammer locking arm thereon, said locking arm being disposed in the path of movement of said hammer extension whereby movement of said hammer to cocked position

will cause pivotal movement of said member to a blocking position, a hammer engaging arm on said member disposed to facially engage said hammer locking surface when said member is in blocking position, means for retaining said member in blocking position against the releasing force of the said spring-urged hammer comprising a sear pivotally moveable from a member locking position in engagement with said locking arm to a released position; a trigger; a connector pivotally mounted on said trigger for moving said sear to released position, and means for disengaging said connector from said sear when said sear reaches released position.
